UNITED STATES PATENT OFFICE.

JOHN J. TRESIDDER, OF NEW YORK, N. Y., ASSIGNOR TO AMERICAN COLUMN COMPANY, OF BROOKLYN, NEW YORK, A CORPORATION OF NEW YORK.

COLUMN AND COLUMN-CAP.

No. 820,155.

Specification of Letters Patent.

Patented May 8, 1906.

Application filed October 23, 1905. Serial No. 283,913.

To all whom it may concern:

Be it known that I, JOHN J. TRESIDDER, a citizen of the United States, residing in New York, in the borough of Brooklyn and State of New York, have invented certain new and useful Improvements in Columns and Column-Caps, of which the following is a specification.

The object of this invention is to furnish for fireproof buildings an improved column and column-cap which are constructed of metal and concrete in such a manner that the same can resist the destructive influence of a fire in a higher degree than cast-iron or other columns, while at the same time the strength of the same is considerably increased; and for this purpose the invention consists of a column which comprises an interior tubular shell or core, an exterior shell or jacket, an intermediate filling of concrete, a base, and a column-cap, which are attached, respectively, to the upper and lower ends of the composite column formed of the interior shell or core, exterior shell, and concrete filling, as will be fully described hereinafter and finally pointed out in the claims.

In the accompanying drawings, Figure 1 represents a vertical central section of my improved column and column-cap. Fig. 2 is a side elevation of the same, partly in vertical transverse section on line 2 2, Fig. 1, through the beam supported on the column-cap; and Fig. 3 is a horizontal section on line 3 3, Fig. 1.

Similar letters of reference indicate corresponding parts in the different figures of the drawings.

Referring to the drawings, *a* represents an interior tubular core, and *b* an exterior shell or jacket, both core and jacket being made of cast-steel or other suitable metal. The lower ends of the core and jacket are supported in the socket *b*² of a base *b*', while their upper ends are inserted into the socket *c*² of a column-cap *c*, which cap is provided with strengthening-ribs *c*' at diametrically opposite sides. The lower end of the socket *c*² is diminished in thickness, so as to form an annular space around the interior core or shell. The socket *c*² of the column-cap *c* below the ribs *c*' is diminished in diameter, so as to form a shoulder against which the exterior shell or jacket *b* is fitted. The socket *b*² of the base *b*' as well as the socket *c*² of the column-cap

c are connected by transversely-extending bolts *d* *d*', which pass through the walls of the cap and base, exterior jacket, and interior core and are tightly attached thereto by screw-nuts *d*², screwed over the threaded ends of the bolts, as shown clearly in Fig. 1. The space between the core *a* and jacket *b* is filled with concrete or other fireproof material.

The I-beams *i* are supported on the beam-seats of the column-cap *c* and secured in position by an upright flange *e*, which is made integral with the cap and connected by a curved transverse portion *e*', said flanged portion being attached by cross-bolts *e*² to the webs of the I-beams. The upper part of the column-cap serves as a base for supporting the next column above and is used in place of the base *b*', and so on, as the different floors of the fireproof building are built. The transverse portion *e*' of the column-cap *c* is connected with the lower part of the next column by a fastening-bolt *f*, as shown in Fig. 1.

The parts of the improved column are assembled before being placed in position by placing the column-cap in inverted position, then inserting the upper end of the interior core or shell *a* into the same, next casting a fireproof filling, such as concrete or other fireproof material, in the annular space of the socket *c*² surrounding the same, care being taken that the core *a* is placed into axial alignment with the center line of the socket *c*². The exterior shell or jacket *b* is then placed in position on the exterior of the socket of the column-cap and attached thereto by the transverse bolt *d*' and the screw-nut *d*². The space in the tubular core and the space between the same and the outer jacket or shell are then filled up with concrete or other fireproof material on a level with the opposite ends of the same. The compound column thus obtained is then inverted and inserted in upright position into the socket of the base *b*' and attached thereto by the bolt *d* and screw-nut *d*², the column being then ready to be placed in position, after which the I-beams are placed on the respective seats on the column-cap and connected with the flanges and intermediate portion of the same by the bolts *e*². The next column is then assembled and placed into the socket formed by the flanges *e* and bolted thereto, and so on all through the building.

The advantages of my improved column are, first, that the same is made of fireproof material throughout and capable of resisting effectually the high temperatures incidental to a destructive fire without warping, cracking, or other injury to the same, so as to obviate thereby the defects of the columns of cast metal; secondly, that the column is of great strength, as the strength of the steel shells is combined with that of the intermediate concrete filling, which binds the shells together and forms a compound column of superior resistance against fire.

Having thus described my invention, I claim as new and desire to secure by Letters Patent—

1. A fireproof column, consisting of an interior core or shell, an exterior shell or jacket, a base for supporting the lower ends of the core and jacket, a column-cap provided with a socket for the upper ends of the core and jacket, transversely-extending bolts for connecting the walls of the base and column-cap

with the core and jacket, and a fireproof filling for the interior of the core and jacket.

2. A fireproof column, consisting of an interior core or shell, an exterior shell or jacket, a base for supporting the lower ends of the core and jacket, a column-cap provided with a socket fitting over the upper end of the core and an exterior circumferential shoulder for the exterior jacket or shell, the wall of said socket being reduced in thickness at its lower portion and spaced from the wall of said interior core; means for attaching the core and jacket to the sockets of the base and column-cap, and a filling of fireproof material for the interior of the core and jacket.

In testimony that I claim the foregoing as my invention I have signed my name in presence of two subscribing witnesses.

JOHN J. TRESIDDER.
